UNITED STATES PATENT OFFICE.

WILLIAM ALBERT CHAPMAN, OF YELLVILLE, ARKANSAS.

MINER'S KNIFE.

SPECIFICATION forming part of Letters Patent No. 594,984, dated December 7, 1897.

Application filed April 13, 1897. Serial No. 631,884. (No model.)

To all whom it may concern:

Be it known that I, WILLIAM ALBERT CHAPMAN, a citizen of the United States, residing at Yellville, in the county of Marion and State 5 of Arkansas, have invented certain new and useful Improvements in Miners' Knives; and I do hereby declare the following to be a full, clear, and exact description of the invention, such as will enable others skilled in the art to 10 to which it appertains to make and use the same.

This invention relates to miners' knives; and it consists, primarily, of a knife proper, a fuse-cutter, a cap-crimper, and a cap-seater combined in one device.

15 The invention further consists of the construction and arrangement of the several parts, which will be more fully hereinafter described and claimed.

The object of the present invention is to 20 provide a combined device of the character set forth wherein the parts are simple and effective in their construction and operation and will facilitate the arrangement and crimping of a cap for blasting and other purposes.

25 In the drawings, Figure 1 is a perspective view of a knife embodying the invention and shown closed. Fig. 2 is a side elevation of the improved knife, showing a portion thereof raised for operation. Fig. 3 is a longitudinal 30 vertical section of the knife, taken through the center thereof.

Referring to the drawings, wherein similar numerals of reference are employed to designate corresponding parts in the several views, 35 the numeral 1 indicates a frame composed of oppositely-disposed pieces of suitable material, which are secured together and provided with a back spring 2 and a knife-blade 3. The edges of the pieces composing the frame 40 on their back portions are formed with oppositely-disposed recesses 4, preferably curved, and the back spring 2 is in like manner bent or depressed at the point of passage around the recesses 4 and slotted to permit a portion 45 of the cutting edge of the knife-blade 3 to project therethrough and be exposed for engagement with devices which will be herein-after more fully set forth.

The one end of the frame 1, at about the 50 central portion thereof, has the opposite parts constructed with grooves 5, with outer beveled faces to form a crimping-recess and the

exposed edges, which, in combination with mechanism coacting therewith, will form a crimp in a cap in attaching the latter to a fuse. Below or to one side of the grooves 5 the curved end 6 of a crimping-head 7 is pivotally attached to the frame 1, and the said head has formed therein a double-edged crimping concaved recess 8, which alines with 60 the edges formed in the grooves 5 to insure a proper crimping action at two points on the cap, which is applied to the fuse and operated upon by the said device. The interior surface of the said head 7 conforms to the contour of the end of the frame 1 at this point, so that it can be closely folded thereagainst, and continuing from the said head is a shank 9, having a borer or seater 10 at its free end, and adjacent to said borer or seater on the 70 under side is a bifurcated lug or shoulder 11, forming oppositely-disposed pressing-arms 12, with concaved faces 13. The said bifurcated lug is adapted to enter the recesses 4 and force the fuse down against the exposed 75 portion of the cutting edge of the knife-blade in the cutting operation, and when the said shank is depressed to attain the result stated the exposed portion of the knife-blade passes up into the bifurcation of the said lug and 80 permits the fuse to be entirely severed without tearing, but with a clean cut.

The borer or seater 10 is adapted to be used, as will be readily understood, and the entire shank may be turned outwardly through its 85 pivotal connection in a plane parallel with the frame of the knife, the several parts being constructed to permit this arrangement.

The end of the frame 1, opposite to that to which the crimping-head 7 and the shank 9 are pivoted, is formed with hand-guards 14 of a suitable width, which may be provided by a proper formation at this point and afford greater strength and stiffness in the folding of the blade within the frame, as well as 95 serving as a guard for the hand. The said guards are spaced apart and form a seat for a catch-spring 14', which engages the borer or seater 10 when the shank 9 is closed down against the back of the frame 1 to render the 100 device compact when not in use, the said catch-spring being of such strength as to avoid a disengagement of the borer or seater and the shank 9, which carries the same.

In the operation of the device the fuse may be first cut and the cap applied and crimped through the medium of the crimping device arranged at the end of the knife-frame. The 5 blade 3 may be used independently of the remaining attachments for any other purpose, and when clasped the exposed portion thereof provides a convenient cutter without necessitating the employment of any additional 10 cutting device for the purposes stated. It will also be understood that the recesses 4 and the concaved portions 13 of the bifurcated lug will be constructed as to their curvature to just embrace the fuse which is placed 15 therein and engaged thereby. The extreme end of the shank forming the borer or seater is made slightly larger than a dynamite cap in diameter and is rounded or cylindrical in form for a distance equal to the length of 20 such cap for the purpose of forcing a hole into a dynamite cartridge to receive said cap and fuse.

Other advantages will appear from time to time to those using this device aside from 25 those which have been enumerated, and it is obviously apparent that many changes in the minor details of construction might be made and substituted for those shown and described without in the least departing from 30 the nature or spirit of the invention.

Having thus described the invention, what is claimed as new is—

1. In a miner's knife of the character set forth, the combination of a frame having recesses therein, a knife-blade movably mounted in said frame and adapted to have a portion of its cutting edge exposed through said recesses, and a movable pressure device engaging the said frame exteriorly thereof and co- 35 acting with the said exposed portion of the knife-blade for the purpose of cutting a fuse, substantially as described.

2. In a miner's knife of the character set forth, the combination of a frame having recesses therein, a knife-blade in coaction with 45 said frame having a portion thereof exposed by said recesses, a shank carrying a bifurcated lug and engaging said recesses and knife-blade for the purpose of cutting a fuse, 50 and a back spring as specified, substantially as and for the purposes specified.

3. In a miner's knife of the character set forth, the combination of a frame having recesses therein, a blade mounted in said frame 55 and having a portion thereof exposed by said recesses, a shank pivotally attached to said frame and having a bifurcated lug coacting with said recesses for the purpose of cutting a fuse, means for holding the said shank close

against the back of the knife, and a depressed 60 and slotted back spring, substantially as and for the purposes specified.

4. In a miner's knife of the character set forth, the combination of a knife-frame having end grooves forming double crimping edges 65 and recesses in the back thereof, a shank continuous from the crimping-head, the latter having crimping edges to coact with the edges formed by the grooves in the end of the knife, and the said shank being also provided 70 with a bifurcated lug to engage the recesses in the back of the knife-frame, a blade mounted in the said frame and having a portion thereof exposed by said recesses, means for holding the said shank close against the 75 knife-back, and a back spring, substantially as described.

5. In a miner's knife of the character set forth, the combination of a frame having grooves at one end thereof forming and exposing double edges, and a crimping-head co- 80 acting with said grooves having double edges and carried by a shank adapted to be locked against the back of the frame, substantially as and for the purposes specified.

6. In a miner's knife of the character set forth, the combination with a frame having recesses therein and provided with a cutting-blade which has a cutting edge exposed 85 through the said recesses when closed into the frame, of a shank pivotally connected to the frame at one end and provided with pressing-arms to align with the said recesses, and a back spring also having a slot depressed 90 therein, substantially as and for the purposes 95 specified.

7. In a miner's knife of the character set forth, the combination with a frame, of a blade mounted therein, said frame being formed with recesses at the back thereof and grooves 100 at one end, a crimping-head pivotally attached to said knife-frame and having crimping edges coacting with the grooves in the end thereof and provided with a shank having a bifurcated lug operating in connection with 105 the recesses in the back of the frame and also with a borer and seater at the free end, means for holding the said shank close against the back of the knife, and a back spring having a slot and depression therein, substantially 110 as and for the purposes specified.

In testimony whereof I have signed this specification in the presence of two subscribing witnesses.

WILLIAM ALBERT CHAPMAN.
